UNITED STATES PATENT OFFICE.

CHESTER W. ALBRIGHT, OF DANVILLE, ILLINOIS, ASSIGNOR TO FRED A. DALEY, OF CHICAGO, ILLINOIS.

REVOLVING-LEAF TREATING-TABLE.

1,076,475.

Specification of Letters Patent.

Patented Oct. 21, 1913.

Application filed January 26, 1911. Serial No. 604,705.

To all whom it may concern:

Be it known that I, CHESTER W. ALBRIGHT, a citizen of the United States, residing at Danville, county of Vermilion, State of Illinois, have invented a certain new and useful Improvement in Revolving-Leaf Treating-Tables, and declare the following to be a full, clear, and exact description of the same, such as will enable others skilled in the art 10 to which it pertains to make and use the same, reference being had to the accompanying drawings, which form a part of this specification.

My invention has for its object to produce 15 a treating table which will enable the physician, without the use of swings or other appliances, to loosen and to adjust the spines of patients in a simple and easy manner; produce several movements and combination 20 of movements throughout the entire lumbar and dorsal regions of the spine; and to swing the spine, in the manner desired, of aged persons, fleshy individuals, cripples, rheumatics and others who cannot now be 25 treated satisfactorily with the appliances available; all of the various manipulations being effected while the patient's muscles are perfectly relaxed and without irritating the patient's muscles, knees and other parts.

30 A further object of my invention is to produce a table of the kind specified which may be locked so as to form a rigid apparatus and thus serve as an ordinary treating table.

35 A further object of my invention is to provide a simple and effective means whereby a patient may brace himself and prevent himself from being pushed or rolled from the table during treatment.

40 The various features of novelty whereby my invention is characterized will herein-after be pointed out with particularity in the claims; but, for a full understanding of my invention and of its object and advantages, reference may be had to the following detailed description taken in connection with the accompanying drawings, wherein:

Figure 1, is a perspective view of my improved table with a patient lying thereon; 50 Fig. 2, is a plan view of the table showing, in dotted lines several positions into which the movable part of the table may be turned; Fig. 3, is a bottom plan view of the table on a larger scale; Fig. 4, is a central longitudinal section through the table; Fig. 5,

is an end view, looking toward the left in Fig. 4; Fig. 6, is a side view of a portion of one end of the table on a larger scale; Fig. 7, is a top plan view of a part of the table, the upholstering being omitted; and Fig. 8, is a side elevation of an adjustable crupper strap which aids in keeping the patient on the table.

In accordance with my invention, I make a table having two leaves which are movable angularly relative to each other and which may be locked together in one or more relative positions so as to present a rigid top. In the arrangement shown, A and B represent the two leaves, the member 65 A extending almost the entire length of the supporting structure or frame C, and the member B overhanging the frame at one end. The member B is in the form of a leaf, which normally forms a continuation 70 of the stationary leaf and, when locked in this position, serves to produce a long, solid, substantially rectangular table which may be used as an ordinary treating table. I prefer so to arrange the parts that the 75 swinging leaf may be turned in either direction from its normal position through a considerable angle as indicated in dotted lines in Fig. 2. The meeting ends of the two leaves are curved so that no gap is produced between them when the swinging leaf is moved. In the arrangement shown, the 80 end of the swinging leaf is convex, while the corresponding end of the stationary leaf is concave. It is obvious that this arrangement might, however, be reversed. The 85 swinging leaf is mounted to turn about an axis approximately at the end of the supporting frame and coincident with the center of the segmental end of the leaf. Therefore a considerable portion of the swinging 90 leaf overlies the supporting frame and causes the leaf to be solidly supported. In Fig. 2, the axis of rotation of the leaf is indicated at b. It will be seen that when a 95 patient is lying upon the table and the swinging leaf is turned, the portion thereof which rests upon the supporting frame moves in the opposite direction from the portion which extends beyond the frame. Consequently, a powerful twisting and bending 100 effort is exerted upon a patient lying upon the table while the swinging portion is moved.

The two leaves of the table are interlocked 110

in any suitable manner in the vertical direction so that the inner end of the swinging leaf is held down and the leaf is prevented from tilting under the weight of the patient. 5 This interlocking of the two leaves may be effected in any suitable way. In the arrangement shown, there is a segmental metal plate D secured to the under side of the swinging leaf in such a position that it projects slightly beyond the same and forms a narrow annular flange about the curved end of the same. This flange extends under the bottom of the stationary leaf so that the swinging leaf cannot be tilted without raising the stationary leaf. By making the construction sufficiently solid, the stationary leaf will serve to hold the swinging leaf firmly and, when a patient is resting upon the table, that portion of his weight borne 10 by the stationary leaf aids the latter in holding down the swinging leaf. The segmental member D is provided with a series of peripheral notches d, d¹ and d² which are adapted to be engaged by a nose e on a locking member, (see Figs. 3 and 7,) so as to secure the swinging leaf in any one of several adjusted positions. The locking device may conveniently consist of two levers E and E¹ pivoted underneath the stationary 15 leaf of the table between their ends, and extending transversely of the table. The meeting ends of the two levers are interlocked as indicated in e¹ so that when one of the leaves is swung on its pivot a corresponding movement is produced at the other. The outer ends of the two locking levers extend to the sides of the table so that an operator at either side of the table may lock and unlock the swinging leaf at will. 20 The pivotal support of the swinging leaf may be constructed in any suitable manner. I have shown in the drawings a simple and satisfactory arrangement, which serves not only as a pivotal support, but also as a stiffening means for the table. Referring to the drawings, particularly Figs. 3 and 4, F represents a Y-shaped metal member fastened to the underside of the stationary leaf and having its stem F¹ projecting forwardly beneath the swinging leaf and to a point somewhat beyond the end of the supporting frame. G is a piece of metal in the form of a flat triangle and this is secured to the underside of the swinging leaf 25 in such a position that one apex g of the triangle overlies the outer end of the member F¹. H is a brace which is secured at one end to the under side of the swinging leaf at the base of the triangular member G and extends inwardly and downwardly toward the supporting frame where it rests upon a transverse seat. In the arrangement shown, the transverse seat is formed by securing a bar I to the two table legs C¹ and C². K is 30 a vertical rod or shaft which passes through

and is journaled in the apex g of the member G, the underlying portion F¹ of the member F, the lower end of the member H and the bar I. The swinging leaf, therefore, turns about the member K and is held against tilting by the member D on one side of the axis and the member H on the other side. 70

One other feature of my invention consists of an adjustable device to which the patient may hold so as to prevent himself from being rolled from the table. This device, (see Fig. 8) may conveniently take the form of a loop l secured to one end of an adjustable strap L which is provided with a hook, or the like, l¹ for attaching it to the table. Secured to the sides of the supporting frame of the table and beneath the stationary leaf are a series of eyes M into any one of which the hook l¹ may be inserted. 80 In the condition of the parts illustrated in Fig. 1, the attachment is shown as hooked underneath the table, the looped end being carried up over the stationary leaf and being slipped over the arm of the patient. It 85 will be seen that the operator may press against the shoulders of the patient without tending to move him across the table, the holding device acting as an abutment to prevent such movement. In other positions of 90 the patient than that indicated in Fig. 1, the holding device may be hooked to a different eye beneath the table or to one of the eyes at the sides of the same. The strap as shown is provided with a buckle l² so that its 100 length may be adjusted to suit the conditions of its use.

The swinging leaf of the table is provided with a detachable and adjustable leg rest O; this consists of a U-shaped member 105 carried upon the outer ends of two sliding metal rods o which pass through suitable keepers P on the under side of the swinging leaf. The U-shaped rest may be slid in and out, the friction between the keepers and the supporting rods being sufficient to hold it in its adjusted positions. When the leg rest is not needed it is simply pulled out until the rods leave the keepers. 110

The table leaves, as well as the leg rests 115 may be suitably upholstered as indicated at A¹, B¹ and O¹, respectively.

I prefer to make the arc of the segmental end of the swinging leaf longer than the arc through which the leaf is adapted to 120 swing, thus making it unnecessary to cut away any considerable portions of the stationary leaf for the purpose of preventing interference at the limit of the swinging movement. This produces jogs B² in the 125 sides of the swinging leaf, but does not materially modify the shape of the table, and at the same time it does away with the objectionable gaps which would otherwise be formed at the corners of the stationary leaf. 130

While I have illustrated and described with particularity only a single preferred form of my invention, I do not desire to be limited to the details of construction so 5 illustrated and described; but intend to cover all forms and arrangements which fall within the terms of the definitions of my invention constituting the appended claims

I claim:

10 1. A treating table having its top composed of a stationary leaf and a swinging leaf, said swinging leaf being pivoted so as to swing about an axis extending transversely to the plane of the table top at a 15 point considerably removed from both ends of the swinging leaf, and a rest carried upon the outer end of the swinging leaf.

20 2. A treating table comprising a rigid frame, a swinging leaf resting upon one end of the frame and projecting beyond the same, said swinging leaf being pivoted so as to be movable in a horizontal plane, and a stationary leaf secured upon said frame and forming with the other leaf the top of the 25 table, the adjacent ends of said leaves leaf so as to form therewith the top of the leaf from tilting.

30 3. In a treating table, a rigid supporting frame, a leaf having one end resting upon the frame and the other end projecting beyond the same, a pivotal connection between the aforesaid leaf and the frame at a point between the ends of the leaf for permitting the leaf to swing in a horizontal plane, and 35 a stationary leaf secured upon said frame adjacent to the inner end of the aforesaid leaf so as to form therewith the top of the table.

40 4. In a treating table, a rigid supporting frame, a leaf having one end resting upon the frame and the other end projecting beyond the same, a pivotal connection between the aforesaid leaf and the frame at a point between the ends of the leaf for permitting 45 the leaf to swing in a horizontal plane, and a stationary leaf secured upon said frame

adjacent to the inner end of the aforesaid leaf so as to form therewith the top of the table, said leaves being interlocked so as to prevent the swinging leaf from tilting. 50

5. In a treating table, a supporting frame, two leaves arranged end to end upon said frame, one of said leaves being pivoted between its ends so as to be capable of swinging in the plane of the leaves, the adjacent 55 ends of said leaves being curved into arcs of circles having their center at the pivotal axis of the swinging leaf.

6. In a treating table, a supporting frame, two leaves arranged end to end upon said 60 frame, one of said leaves being pivoted between its ends so as to be capable of swinging in the plane of the leaves, the adjacent ends of said leaves being curved into arcs 65 of circles having their center at the pivotal axis of the swinging leaf, and means for locking the swinging leaf against movement.

7. A treating table, a supporting frame, two leaves arranged end to end upon and 70 supported by said frame, one of said leaves being pivoted at a point between its ends so as to be capable of swinging in the plane of the other leaf.

8. A treating table having an approxi- 75 mately rectangular top containing sections whose adjacent edges are curved about a common center in the arc of a circle having a diameter approximately equal to the width of the table, and a portion of the top ex- 80 tending on opposite sides of said center in the direction of the length of the table and forming one end of the top and being movable around a vertical axis passing through said center. 85

In testimony whereof, I sign this specification in the presence of two witnesses.

CHESTER W. ALBRIGHT.
